UNITED STATES PATENT OFFICE.

EDWARD C. SEVIGNY, OF JACKSONVILLE, FLORIDA.

SEAMLESS-TUBE-DRAWING BENCH.

1,302,599.

Specification of Letters Patent.

Patented May 6, 1919.

Application filed November 5, 1918. Serial No. 261,312.

To all whom it may concern:

Be it known that I, EDWARD C. SEVIGNY, a citizen of the United States of America, residing at Jacksonville, in the county of 5 Duval and State of Florida, have invented certain new and useful Improvements in Seamless-Tube-Drawing Benches, of which the following is a specification, reference being had therein to the accompanying drawing.

The invention relates to benches and more particularly to benches used for drawing seamless tubes. Benches in use, at the present time, require at least two operators to 15 operate the same. It is one of the objects of the present invention to provide a bench, wherein the number of operators may be reduced to a minimum, in fact a bench that can be operated by one man.

20 A further object of the invention is to provide a tube drawing bench, wherein the tube is grasped by a clamping member at the die, then drawn through a die by a movable clamping member to any desired length. 25 also to provide means whereby the movable clamping member may be returned to its initial position at any desired time.

A further object of the invention is to 30 provide a tube drawing bench and a tube clamp carried by a carriage, said carriage being provided with means whereby the carriage will be moved along the bench by means of a moving element, and means whereby the carriage may be disengaged, 35 from the moving element and returned to its initial position from any point along the bench.

With the above and other objects in view, 40 the invention resides in the combination and arrangement of parts as hereinafter set forth, described and shown in the drawings, it being understood that changes in the precise embodiment of the invention may be made within the scope of what is claimed 45 without departing from the spirit of the invention.

In the drawings:—

Figure 1 is a side elevation of the drawing bench, showing the carriage in position for 50 the tube drawing operation.

Fig. 2 is a longitudinal sectional view of the tube drawing bench, showing the carriage in position for starting and the dog in engagement with the chain.

5 Fig. 3 is a top plan view of the bench.

Fig. 4 is a sectional view on line 4—4 of Fig. 3.

Fig. 5 is a detail view of the clutch operating yoke.

Fig. 6 is a top plan view of the carriage 60 showing the clamping jaws in open position.

Fig. 7 is a side elevation of the carriage showing the same in operating position.

Fig. 8 is a sectional plan view on line 65 8—8 of Fig. 7.

Fig. 9 is a longitudinal sectional view taken on line 9—9 of Fig. 6.

Referring to the drawings, the numeral 1 designates a conventional form of pipe 70 drawing bench, which comprises the parallel sides 2 transversely spaced by means of cross pieces 3, said cross pieces may be of any construction. The sides 2 are provided with a series of supporting legs 4 75 adapted to be secured to the flooring of a building or on a base for preventing displacement of the bench during a tube drawing operation. Rotatably mounted in bearings 5 and 6, at the ends of the sides of 80 the draw bench are shafts 7 and 8 and secured to these shafts by means of pins 9 are sprockets 10 and 11 and extending around the sprockets 10 and 11 is an endless sprocket chain 12. Secured to one end 85 of the shaft 7 is a gear 8, also secured to the shaft 7 is a conventional form of pulley 13, to which power may be imparted through a belt or from any suitable means. From the above it will be seen, that when revoluble 90 movement is imparted to the pulley 13, and sprocket 10, that the sprocket chain 12 will be caused to move in the direction of the arrow *a*, Fig. 2, which movement is a continuous one in this direction at all times. 95

A conventional form of die 14 is mounted in the vertical slot 15 at one end of the bench and is secured therein by means of a set screw 16, however this structure may be of any form that is commonly used at 100 the present time.

Slidably mounted and disposed over the sprocket chain 12 is a tube carriage clamp 17, said carriage being mounted on the upper edges 18 of the sides 2 by means of 105 the flanged wheels 19, which rotate on pins 20 secured to the sides of the carriage 17. The forward end of the carriage is provided with a recess 21 and rotatably mounted on pins 22 in said recess are rollers 23 and 110

24, which act to open and close the toothed tube clamping jaws 25, of the tube clamp 26. The tube clamp 26 comprises two members 27 and 28 which are pivoted and secured together by means of a pin 29, the lower end of which moves in an elongated slot 31, while its upper end extends upwardly through an elongated slot 32, the purpose of which will presently appear.

10 Pivots secured to the upper end of the pin 29, as at 33, is a lever 34 which in turn is pivoted at 35 to the cover 36 of the carriage, said cover being secured to the body thereof by means of screws 37. It will be seen that when the lever 34 is rocked, that the arms 38 of the clamping jaws which engage between the rollers 23 and 24 will be caused to open and close according to the direction of movement of the lever 34, therefore by opening and closing the jaws 25 of the tube clamp for grasping or releasing the tube. A chain engaging dog 40 is slidably mounted in an aperture 41, at the rear of the carriage said dog being provided with a recess 42 which is engaged by one of the rollers 43, of the sprocket chain 12 when it is desired to draw the tube through the die 14. Pivots secured at 44, to the upper end of the post 45, is a rockable lever 46, one end of which is secured to the upper end of the dog 40 as at 47, there being an elongated slot 48 to allow movement of the parts, a pin 49 being provided to limit downward movement of the dog 40. The other end of the rockable lever 46 is provided with an adjustable weight 49, the purpose of which will presently appear. Extending upwardly from the carriage 17 is a post 50, which is provided with an adjustable sleeve 51 whereby the downward movement of the weighted end of the lever 46 may be limited.

Rotatably mounted in bearings 52, at the rear end of the bench is a shaft 53, and secured to one end of said shaft 53 is a gear 54, which meshes with the gear 8, said gear 8 when rotated imparting revoluble movement to the shaft 53 through the medium of the gear 54. Rotatably mounted upon the end 55 of the shaft 53 is a cable drum 56, which is provided with a female clutch recess 57, adapted to receive the male portion of the clutch 58, which is keyed to the end of the portion 55 of the shaft. Interposed between the cable drum 56 and the clutch member 58 is a coiled spring 58^a, which keeps the parts normally separated and the cable drum in engagement with a thrust bearing 59. A sliding clutch collar 60 is disposed between the thrust bearing and an annular rib 61, on the shaft 53, thereby limiting the inward movement of the clutch collar 60. These rotating parts carried by the portion 55 of the shaft are lubricated through the medium of the oil slot 62, oil

passage 63 and oil cup 64 thereby thoroughly lubricating the parts at all times. Secured at 65 to the cable drum is a cable 66, which leads forwardly through guides 67, thence around the pulley 68, which rotates upon a pin 69 and the cable end is secured to the end of the lever 34, as at 70. Secured to the side 2, of the bench is a bearing 71 and vertically mounted in said bearing is the shaft 72, of a clutch operating member, said shaft being prevented from vertical movement in its bearing by means of the collars 73, which are pinned thereto. The lower end of the shaft 72 is provided with an arm 74, which terminates in a clutch operating yoke 75, the arms of which are provided with lugs 76 adapted to engage a groove 77 of the sliding collar 60. The upper end of the vertical shaft 72 is provided with an arm 78 and to which arm one end of an operating rod 79 is adjustably connected, said rod 79 extending forwardly through guide eyes 80 and having its other end adjustably secured as at 81, to the arm 82, of the foot lever 83, which is pivoted to one of the legs 4, of the side frame 2, as at 84. The arm 85 of the lever 83 is provided with a foot piece 86 adapted to be engaged by the foot of the operator when it is desired to operate the clutch.

The operation is as follows: When it is desired to draw a tube, the carriage 17 is in a forward position so that the jaws 25 of the tube clamp will grasp the tube at the die 14. While in this position the arm 34 carrying the clamping members is moved forwardly so that the jaws 24 thereof will grasp the tube. The lever 46 being in a down position as shown in Fig. 1 is then pulled upwardly until the dog 40 is engaged by one of the rollers 43, of the endless chain 12, as shown in Fig. 2, after said engagement the carriage 17 will move rearwardly on the bench and consequently draw the tube through the die 14. When the tube has been drawn to a sufficient length, to disengage the tube from the clamping jaws, stop the carriage 17 and return the same to its initial position, the operator places his foot on the foot lever tread 86, thereby pulling the rod 79 and consequently rocking the yoke 74, which yoke through the medium of the sliding member 60, causes the cable drum 56 to be moved longitudinally on the portion 55 of the shaft 53, against the action of the spring 58^a and into engagement with the male member 58 of the clutch, which rotates with the shaft. This action causes the winding of the cable 66, on to the cable drum, thereby imparting a pull upon the arm 34, consequently moving the tube clamp, as a whole rearwardly and spreading its arms 38 thereby releasing the tube. After the tube is released, the weight 49 will cause the lever 46 to pivot at 44 and raise the

chain engaging dog 40 out of engagement with the roller 43, of the endless chain 12. The further pulling of the cable 66, returning the carriage 17 to its initial position for drawing another tube through the die.

From the above operation it will be obvious that a tube drawing bench is provided, that will require only one man to operate, and it will also be seen that a bench is provided that will draw tubes of any desired length at the option of the operator and that the tube drawing clamp and carriage, will be automatically released from the endless chain and returned to initial position at the option of the operator.

The invention having been set forth, what is claimed as new and useful is:—

1. A tube drawing bench comprising a movable chain mounted in a frame, a carriage mounted on said frame and provided with a pair of clamping jaws for grasping and releasing a tube, a lever pivoted on the carriage for closing and opening said clamping jaws, a dog carried by the carriage and adapted to be moved into and out of engagement with the movable chain, a weighted lever connected to said dog for disengaging the dog from the movable chain, and means connected to the lever on the carriage whereby the lever will be rocked, the clamping jaws opened so as to release the tube, the weighted lever allowed to disengage the dog from the movable chain and the carriage returned to initial position for drawing another tube.

2. A tube drawing bench comprising a frame having a movable chain therein, a carriage mounted on said frame and having a pair of clamping jaws for grasping and releasing a tube, a lever pivoted on the carriage for closing and opening said clamping jaws, a dog carried by the carriage and adapted to engage and disengage the movable chain, means coöperating with the dog for disengaging the dog from the chain when the tube is released by the clamping jaws, and a cable connected to the pivoted lever on the carriage whereby a pull may be imparted on the cable for rocking the lever and opening the clamping jaw and allowing the means coöperating with the dog to disengage the dog from the movable chain and the further pull upon the cable to return the carriage to initial position for drawing another tube.

3. A tube drawing bench comprising a frame having a movable chain therein, a carriage mounted on the frame and having a pair of clamping jaws for grasping a tube,

a lever pivoted on the carriage for closing 60 and opening said clamping jaws, a dog carried by the carriage and adapted to engage the movable chain, said dog having a weighted lever connected thereto for releasing the dog from the movable chain, a 65 carriage return cable connected to the pivoted lever, means for imparting a pull upon said cable for rocking the lever, releasing the tube from the clamping jaws, allowing the weighted lever to disengage the dog 70 from the movable chain and returning the carriage to initial position for drawing another tube.

4. A tube drawing bench comprising a frame having a movable chain therein, a carriage mounted on said frame and having a pair of clamping jaws for grasping and releasing a tube, a lever pivoted on the carriage for closing and opening said clamping jaws, said carriage being provided with a 80 dog for engaging the movable chain, a weight for disengaging said dog from said chain, a cable connected to said carriage lever and means for imparting a pull upon the cable at any time during the drawing 85 operation for disengaging the tube from the clamping jaws, allowing the weight to disengage the dog from the movable chain and returning the carriage to initial position for drawing another tube. 90

5. A tube drawing bench comprising a frame having an endless movable chain mounted therein, a carriage mounted on a raceway and disposed over said movable chain, a pair of clamping jaws carried by 95 said carriage for grasping a tube during a drawing operation, a lever pivoted on the carriage for closing and opening the clamping jaws, a dog carried by the carriage for engaging the endless movable chain during 100 a tube drawing operation whereby the carriage will be moved on the raceway, a weighted lever connected to the dog and adapted to disengage the dog from the chain when the tube is released from the clamping 105 jaws, a clutch controlled cable connected to the pivoted lever on the carriage, and means for imparting a pull upon the cable the initial pull of which will rock the pivoted lever thereby opening the clamping jaws 110 and release the tube allowing the weighted lever to disengage the dog from the chain and the further pull upon the cable return the carriage to initial position for drawing another tube. 115

In testimony whereof I hereunto affix my signature.

EDWARD C. SEVIGNY.
